UNITED STATES PATENT OFFICE.

WILLIAM DALTON, OF SCHENECTADY, NEW YORK, ASSIGNOR TO
AMERICAN LOCOMOTIVE COMPANY, OF NEW YORK, N. Y., A
CORPORATION OF NEW YORK.

LOCOMOTIVE-TRUCK.

No. 823,491.

Specification of Letters Patent.

Patented June 12, 1906.

Application filed August 28, 1905. Serial No. 276,220.

To all whom it may concern:

Be it known that I, WILLIAM DALTON, of Schenectady, in the county of Schenectady and State of New York, have invented a certain new and useful Improvement in Locomotive-Trucks, of which improvement the following is a specification.

My invention while more particularly designed for application in the leading-trucks 10 of electric locomotives is likewise applicable without change of structural or operative principle in steam-locomotive trucks; and its object is to provide means whereby the truck may be allowed the lateral motion which is 15 proper and necessary to enable the locomotive to pass freely around curves and quick side motion or "nosing" when traversing straight portions or tangents of the track shall be effectually prevented.

20 The improvement claimed is hereinafter fully set forth.

It has been developed in practice that while the conditions of speed, weight, and wheel-base in electric locomotives may not 25 differ materially from those which obtain in steam-operated machines the difference in the distribution of weight is such that truck constructions which had proven entirely satisfactory in the latter failed to do so in the 30 former. In the electric locomotive the center of gravity is ordinarily only about one-half as high as in the steam-locomotive, and the weight of the machine is concentrated at its middle portion instead of being distributed 35 over the same and the end portions as in steam-locomotives. It is further the fact that the close coupling of the tender to a steam-locomotive tends to steady its motion. As a result of these differences it was found 40 that trucks of a construction which had operated equally well both on curves and tangents when used in steam-locomotives performed satisfactorily in electric locomotives so far as passing curves was concerned, but had a 45 pronounced nosing or quick side motion on straight track, which caused the flanges of the leading driving-wheels to bring up objectionably against the rails and tend to spread the latter, as well as to unduly wear the 50 flanges. My invention is particularly designed to overcome this objection, which end

it attains by the provision of a construction in which resistances to lateral motion which act in concurrence in one direction and in opposition in the other are exerted by the 55 means and in the manner hereinafter described.

In the accompanying drawings, Figure 1 is a front view, in elevation, of a locomotive-truck embodying my invention; Fig. 2, a 60 vertical longitudinal central section through the same; Fig. 3, a plan or top view, partly in section; Fig. 4, a transverse central section, and Fig. 5 a horizontal section through one of the axle-boxes and the adjacent wheel. 65

In the practice of my invention the frame 5 of the truck is preferably, as shown, formed of a unitary steel casting comprising two parallel transverse side members connected at top by a horizontal top member and having 70 pedestals 5^b at their ends, in which the axle-boxes 3 are fitted with the capacity of relative vertical movement, as in the ordinary constructions. The truck-wheels 4 are fixed upon an axle 2, the journals of which rotate 75 in bearings 3^a in the axle-boxes, upon which the truck-frame is supported through the intermediation of springs 9, the lower ends of which are inclosed in recesses or spring-cases at the ends of the top member of the truck-frame. The axle-boxes 3 are made without 80 inside flanges, and their sides abut against angular steel facing-plates 5^d, secured to the pedestal-jaws and serving to protect the latter from wear in service. The frame can 85 thus be readily finished by planing the inner faces of the pedestal-jaws and planing across their outer ends.

The main frame 1 of the locomotive is supported upon the truck-frame 5 in such manner as to admit of the desired and determined degree of relative lateral movement, there being in the instance shown an upper center casting 8, the upper portion of which fits in a socket 8^a, secured to the main frame 90 1, and the lower end of which fits in and abuts on a lower center casting 7, which rests on a frictional bearing-face on the top of the truck-frame. The frictional bearing-face is preferably, as shown, formed upon the top of 100 a friction-plate 6, secured detachably on the top of the truck-frame, which, with the con-

nnected friction-plate, has the capacity of lateral motion relatively to the lower center casting 7 and the main frame 1 of the locomotive, with which the latter is connected through the upper center casting and its socket, as above described. In order to enable the abutting faces of the lower center casting and the friction-plate to be effectively lubricated, an oil chamber 5^a is formed in the top of the truck-frame, said chamber surrounding and extending above the abutting faces, so that they may be maintained continuously submerged in oil to prevent the undue resistance to lateral motion which would result if they were permitted to run dry. Cover-plates 5^c, secured to the truck-frame, project partly over the oil-chamber and are overlapped by a cover-plate 7^a, secured to the lower center casting for the purpose of preventing the access of dust or other foreign matter to the oil-chamber.

In order to return the truck-frame to its normal position in line longitudinally of the locomotive after it has been diverted therefrom in passing a curve, a transverse centering-spring 10 is fitted in an abutment-case 11, which is closed at one end by a removable head 12 and is secured centrally to a support 1^a, fixed to the main frame 1 of the locomotive. The spring 10 abuts at its ends against followers 13, which in turn abut against the heads of the case 11. Thrust members in the form of rods 14 abut at their inner ends on spherical-faced bearings on the followers 13, and their outer ends fit in and abut against spherical sockets 15, fixed to the ends of the truck-frame 5.

It will be seen that under the construction above described the relative lateral movement of the truck-frame and the main frame of the locomotive in passing from a tangent to a curve is opposed by the aggregate of the resistance of the tension of the centering-spring 10 (as, say, three thousand pounds) and of the resistance to movement of the abutting faces of the friction-plate 6 and lower center casting 7, (as, say, two thousand pounds,) being a total of five thousand pounds. In passing from a curve to a tangent the force acting to return the truck-frame to normal position centrally with the main frame is, however, the energy stored in the spring (three thousand pounds) less the opposing resistance of the abutting frictional surfaces, (two thousand pounds,) being a total of only one thousand pounds exerting centering action. As a result of this diminution of centering action while retaining the desired maximum resistance to lateral movement in passing from a tangent to a curve, the locomotive will instead of having a vibrating or nosing action run with entire steadiness.

It will be obvious to those skilled in loco-

motive construction that my invention is not limited to the specific structural details of connection between the truck - frame and main frame which are herein described and shown, as it may be applied without variation of principle in trucks provided with the usual swing links or other appliances for limiting and controlling lateral motion.

The leading and characteristic feature of my invention consists in a construction in which independent spring and frictional resistances are provided and are so related as to act in conjunction in opposing the movement of the truck away from the center and in opposition relatively to the movement of the truck toward the center. Such a construction is, so far as my knowledge and information extend, novel with me, and I therefore intend my claims covering it herein to be of corresponding broad scope.

I claim as my invention and desire to secure by Letters Patent—

1. The combination, in a locomotive, of a main frame, a truck-frame connected, with the capacity of relative lateral movement thereto, a centering-spring interposed between abutments on the main frame and on the truck-frame, respectively, and acting to resist outward lateral movement of the truck-frame and effect inward lateral movement of said frame, abutting friction-faces on the main and truck frames, and an oil-chamber on the truck-frame surrounding and extending above said friction-faces whereby the same may be maintained continuously submerged in a lubricant.

2. The combination, in a locomotive, of a main frame, a truck-frame connected, with the capacity of relative lateral movement, thereto, a centering-spring interposed between abutments on the main frame and on the truck-frame, respectively, and acting to resist outward lateral movement of the truck-frame and effect inward lateral movement of said frame, a friction-plate fixed to the upper portion of the truck-frame, a lower center casting supported on said friction-plate, and an upper center casting fitting in the lower center casting and in a socket fixed to the main frame.

3. The combination, in a lateral-motion truck, of a truck-frame formed of an integral casting comprising two transverse members connected by a horizontal top member and having pedestal-jaws on their ends, a friction-plate fixed on the top member, and an oil-chamber on the top member surrounding and extending above the friction-plate.

4. The combination, in a lateral - motion truck, of a truck-frame comprising two transverse members connected by a top member, and axle-boxes interposed between the pedestal-jaws and having flanges on their outer ends and plane inner ends.

5. The combination, in a lateral-motion truck, of a truck-frame comprising two transverse members connected by a top member, axle-boxes interposed between the pedestal-jaws and having flanges on their outer ends and plane inner ends, and angular facing-
5 plates fixed to the pedestal-jaws, and fitting

between the same and the sides and flanges of the axle-boxes.

WILLIAM DALTON.
